UNITED STATES PATENT OFFICE.

LESLIE SALTER, OF LONDON, ENGLAND.

PORTABLE CHAIN-STITCH SEWING-MACHINE.

1,053,226.

Specification of Letters Patent. Patented Feb. 18, 1913.

Application filed December 19, 1911. Serial No. 666,728.

To all whom it may concern:

Be it known that I, LESLIE SALTER, subject of the King of Great Britain and Ireland, residing at 50 Copthall avenue, London, England, have invented new and useful Improvements in Portable Chain-Stitch Sewing-Machines, of which the following is a specification.

This invention relates to a portable chain 10 stitch sewing machine, and consists of the formation of parts to make the machine a chain stitch sewing machine for household use.

The essential characteristic of this machine is that the driving cam drives through a back pivoted lever whose lower end engages with an under lever also pivoted at about its center, which engages a rocking hook looper, so as to produce a horizontal 20 movement on said looper, its lower end being pivoted on an under link which at its farther end is pivoted on the framing, by which the necessary chain stitch is effected.

In order that this invention may be the 25 better understood, I hereby show drawings of the machine and parts, reference being had to the letters and figures marked thereon.

Figure 1 is a side elevation of the machine. Fig. 2 is a plan thereof taken below 30 the working table showing the hook lever. Fig. 3 is an end view of the needle bar. Fig. 4 is a cross section showing the driving cam and the back lever. Fig. 4^a is a detail view of the eccentric axle for supporting the 35 hand wheel. Fig. 5 is a cross section to show the presser feeding foot with the cam operating it. Fig. 6 is a similar view to Fig. 5 showing the cam in a position to just lift the presser feeding foot which is shown 40 in its extreme position of feed. Fig. 7 is a similar view to Figs. 5 and 6 showing the presser feeding foot lifted.

The metal frame *a* is in the shape of the letter **G** and in its base *a*¹ is the screw *b*¹ 45 which forms the center of the hook lever *b*¹. This hook lever *b*¹ is actuated by a back lever *c* pivoted at *c*¹, Fig. 4, which is actuated by the driving cam *c*¹ attached to the top shaft *d* engaging with the flat head *c*², 50 the said cam being driven by two geared wheels *d*¹ *d*² from the hand wheel *e*. This lever *c* terminates with a finger *c*⁴ which engages with a hole *b*⁴ in the lever *b*¹. These two levers *c* and *b*¹ are kept close to the 55 driving cam by a spring *b*³ underneath the

center of the hook lever *b*¹, one end of said spring being attached to the lever *b*¹ and the other to the framework.

To the front portion of the hook lever *b*¹ is attached a rounded part *b*² which makes 60 connection with a hook looper *f* which is pivoted on a link *f*¹ of which the outer end is pivotally mounted upon the stud *f*² fixed to the framework. This hook looper *f* is supported at its upper portion by an aperture which receives the rounded part *b*² of the hook lever *b*¹ moving horizontally and is thus given a rocking motion about its under link *f*¹, supported by the pivot *f*³ which is part of a rocking link *f*¹ pivoted at its upper end *f*² on to a standard in the framing, so as to enable it to catch and then to release the cotton when the needle is in its lowest position and which thereby forms the chain stitch. 75

The driving wheel *e* is mounted on a pin *e*¹ of which a portion of it *e*² is made eccentric to the outer portion. This is fitted into a sleeve *e*³ which enables the eccentric portion *e*² of the pin *e*¹ to be moved upward, 80 so as to cause the gearing *d*¹, *d*², to engage properly with one another. When this engagement is made the inner eccentric portion of this pin is secured by a screw stud *e*⁴, the outer driving wheel *e* revolving freely on 85 the outer portion *e*¹ of this pin.

Upon the upper shaft *d* at the front end is fitted the feed cam *g* from which both the needle bar *h* and the presser feeding foot *k* are actuated. Upon the outer face of this 90 feed cam *g* is placed as part of it a disk *g*¹ in a hole in which a bent wire *g*² shaped like an **S** forms a connecting rod from the disk to the needle bar *h* one end of the wire entering the hole in the cam and the other end being secured to the needle bar *h*. This 95 needle bar *h* works between two guides *h*¹ over which are two small plates *h*² to allow the needle bar to work freely up and down. The needle *l* is fixed to the lower part of 100 the needle bar *h* by means of a clip or stop *l*¹ with a screw *l*² to adjust the needle, and to prevent it slipping from its working position.

To one side of the needle bar *h* is fitted 105 the presser feeding foot *k*, which is held in a slot *m*¹ in the frame for it, and oscillates about a pin *n* fixed to the frame which passes through a slot *n*¹ in the presser feeding foot. 110

The feeding cam g as it rotates acts upon part of the presser feeding foot, thrusting it out where it revolves about the pin n , fixed at the upper end of the presser feeding foot making an effective feed upon the work as the presser feeding foot is held down by the spring n^2 . The presser feeding foot is also held up against the side reaction by a spring n^3 . When this presser feeding foot has completed its feed, the continued rotation of the cam g comes under an arm m^2 and thus lifts the presser foot for its return.

An adjustment of the stroke laterally of the presser feeding foot is effected by a screwed stud p which reduces the stroke of the feed laterally to a minimum.

A spring pressed cam p^1 (Fig. 3) working on a fixed stud in the frame may be worked by hand to raise the presser feeding foot by engagement with the projecting neck p^2 out of contact with the work.

The reel holder r is fixed by the under portion of this wire being bent at r^1 and passed through the upper portion of the machine above the axle d . The cotton passes through a guide r^2 and through a tension r^3 down to the needle.

To the main driving wheel e is fitted a folding handle s which when it is closed causes a spring pressed knob s^1 to engage with a corresponding depression s^2 . This driving wheel e is provided with a depression t by which a driving band can be attached from an independent foot treadle.

All the above described parts with the usual gearing, work in unison to form a chain stitch sewing machine, with fewer parts than heretofore so as to make it cheap in construction and portable.

Having thus fully described my invention, I claim as new and desire to secure by Letters Patent:—

1. A portable chain stitch sewing machine, having in combination, a pivoted rocking hook looper having means at its upper portion for the insertion of a hook lever to support the same and a pivoted joint at its lowest part, a hook lever moving with a horizontal movement thus supporting the hook looper, a link below the said hook looper pivoted at one end to the under pivot of the said hook looper and at the other end pivoted to the framing, the looper being thus given a rocking motion in combination with the horizontal movement of the said supporting lever, a back lever connected with the hook lever, and a cam

on the driving shaft driving the said back lever.

2. A portable chain stitch sewing machine, having in combination, a pivoted rocking hook looper having a hole in its upper part and a pivoted joint at its lowest part, an under link pivoted at one end to the said looper and at the other end to a fixed standard in the framing, an under pivoted hook lever engaging in the said upper hole of the said hook looper to support the same and to give to it a horizontal movement, a pivoted back lever engaging with the said hook lever, and a cam upon the driving shaft to drive the said back lever.

3. A portable chain stitch sewing machine, having in combination, a pivoted rocking hook looper having a hole in its upper part and a pivoted joint at its lowest part, an under hook lever pivoted on a bolt in the horizontal framing moving horizontally having at one end a pin engaging in the said hole at the upper part of said hook looper and at the other end an aperture, a back lever pivoted on a bolt in the vertical frame engaging by a finger at one end with the said aperture of the said hook lever, and having a flat head at its upper end, and a cam upon the main driving shaft adjacent to the driving wheel driving the said back lever transversely to the vertical back of the machine.

4. A portable chain stitch sewing machine, having in combination, a pivoted rocking hook looper having a hole in its upper part and a pivoted joint at its lowest part, an under hook lever moving horizontally engaging at one end with the hole in the upper part of the said hook looper, a back lever connected to this hook lever, a cam on the driving shaft adjacent to the driving wheel operating the said back lever transversely to the vertical back of the machine, and a horizontal coiled spring about the center of the under hook lever, connected to the under hook lever and to the framework, to press the upper end of the back lever, through the under hook lever by the connection between said levers upon the driving surface of the said cam.

In testimony whereof I have signed my name to this specification in the presence of two subscribing witnesses.

LESLIE SALTER.
